AUTOMATIC SLIDE PROJECTOR

Fred Brunish, Los Angeles, Calif., assignor to
Consolidated Advertising Corp., Ltd., Los Angeles, Calif.

Application May 21, 1934, Serial No. 726,657

9 Claims. (Cl. 88—27)

This invention relates to an automatic slide projector more particularly intended to be used for advertising purposes, but not necessarily restricted to such a use.

5 The invention further pertains to that type of projection machines wherein a series of slides, usually 12 to 48 in number, are arranged to be automatically displayed continuously at definite intervals of a few seconds between each slide, the matter inscribed on a given set of slides being thus repeatedly displayed until new slides are substituted.

An object of the invention is to provide a machine of the aforementioned kind that can be operated in a smaller space for a given size of screen or display field than is possible in the case of machines of this kind which have hitherto been in use. This object is attained by the use of a novel arrangement of reflectors which provides 20 room for expanding the image the required amount without the necessity of building the machine on nearly so large a scale as would otherwise be necessary.

Other objects, advantages and features of invention may hereinafter appear.

Referring to the accompanying drawings, which illustrate what is at present deemed to be a preferred embodiment of the invention,

Fig. 1 is a perspective view of the machine, 30 parts thereof being broken away in order to disclose structures that would otherwise be concealed.

Fig. 2 is a view of the dark chamber structure wherein certain external parts are shown in 35 transverse section; and the remaining parts are shown in plan.

Fig. 3 shows the dark chamber and parts therein in vertical mid-section except that some of the enclosed parts are shown in elevation.

40 Fig. 4 is a fragmental perspective view of part of the projecting elements.

Fig. 5 is an enlarged sectional detail taken on line 5—5 of Fig. 3.

Fig. 6 is an enlarged perspective view of a portion 45 of the means whereby the individual slides are centered in the proper display position.

Fig. 7 is an enlarged perspective view of a part of the slide mounting means.

50 Referring in detail to the drawings, and naming first the principal parts as viewed in Fig. 1, the main casing 10 has at its front end an upstanding image receiving plate 12, desirably made of a suitably colored ground glass. An ornamental border plate 13, which aids in forming the

front wall of the casing, is shown surrounding said plate 12.

Said casing 10 is furnished with a floor portion 14 which supports the casing 15 of a dark chamber 16. Said dark chamber contains, among 5 other things, the slide carrier 17 and projector lamp 18. From the front wall of the casing of the dark chamber extends the tubular lens holder 19 containing a pair of projection lenses 19a and 19b. From said lenses the image is projected 10 forwardly upon the primary mirror 20 located in the front part of the casing within a space provided for it below the image receiving plate 12. From said mirror the image is reflected backwardly and at an upward inclination until it encounters the rearwardly located secondary mirror 21. The image is thus progressively enlarged and is finally thrown forwardly from the secondary mirror 21 to the receiving plate 12 upon which it is displayed to the public. 20

Describing more in detail the construction of the circular slide carrier 17, said carrier comprises a rotatable table the top of which includes a disc 25 mounted concentrically of the post 24, said disc having a central opening 25a to clear 25 the central portion thereof from said post.

Said disc 25 has a series of spaced slide holders 26 mounted in upstanding positions along the peripheral portion thereof. These slide holders are preferably of identical construction, one being 30 shown in detail in Fig. 7. Each includes an angle iron post 27 having a foot portion 28 whereby it is secured to disc 25 with its inner angle directed towards the center of said disc. An inner plate 29 and outer plate 30, both of the same angularity as the post, cooperate with said post to form a holder for the adjacent ends of the picture or image slides 31. At each side of its lower end the outer angle plate 30 has an inwardly directed flange or ear 32 to form a slide support. Said 35 angle plates are riveted or otherwise secured to opposite sides of the post 27 as shown in Fig. 7, the thickness of the post being sufficient to space said angle plates apart sufficiently to provide for ready insertion and removal of the end portions 40 of the slides 31.

The disc 25 has secured to its lower face by screws 25x, a horizontally disposed gear 34 having a hub portion 34a projecting from its lower side. Said hub surrounds the post 24 in a spaced relation thereto, but fits rotatably within a tubular bearing member 34c which upstands from and is secured to the floor 14. The weight of the gear is sustained by an internal annular flange 34f of said bearing member 34c. The gear 34 has an ex- 55

ternal groove 34g surrounding its hub portion and with this groove cooperates a tension spring 34h under pressure from a screw 34k tapped thru the bearing member 34c.

- 5 Said gear 34 has teeth 35, said gear being the final gear of a train of gears which rotates said disc. Said gear 34 is intermittently rotated one tooth at a time by means of a stud or pin 36 which upstands from a horizontally disposed gear 10 37, the teeth of which are in mesh with a pinion gear 38. Gear 37 is rotatably mounted upon a vertical shaft 39 and gear 38 is fixed to a live shaft 40. Below pinion gear 38 shaft 40 has fixed to it a gear 41 that is in mesh with the 15 worm gear 42 fixed to the shaft 43 of the motor 44.

In order to prevent over-rotation of the slide carrier 17 when the gear teeth 35 (see Fig. 6) are acted upon by the pin 36 of the gear 37, and 20 also to position accurately each of the eight slides shown when it comes opposite to the lens holder 19, a control spring 45 is provided. This is a leaf spring having a seat 45s bent thereinto at a point intermediate its end portions to cooperate 25 with the points of gear teeth 35. Said spring may be arranged to provide a braking surface 45b near its free end which surface frictionally engages said gear teeth to prevent over-rotation. Near its other end said spring is shown secured 30 to a bracket 46 to which it is adjustably related in a double manner owing to the fact that said bracket has a tubular body 47 to receive the turnable and extensible spring supporting pin 48. A set screw 49 holds said pin in the adjusted position. The bracket 46 has a bifurcated foot 50 35 to provide for its convenient attachment to any suitable support. Steadiness of rotation is further assured by the tension spring 34h of Fig. 5, which has already been described.

40 The post 24 is of a tubular character in order that the lamp cord 55 may be led therethru to supply current to the electric lamp 18 already mentioned, which is mounted upon the top of said post. Said post, together with the other vertical shafting which has been mentioned, may 45 upstand from and be fixed to the floor 14 of the main casing, the floor of the dark chamber 16 being a continuation of the floor of the main casing.

50 With the lamp 18 cooperates an assembly of optical elements which is shown surrounded by the operatively mounted plurality of slides 31 and which need not be described in detail, as it may be varied to suit the operator without departing from the spirit of the invention as defined by the claims. It will, therefore, suffice to mention that a concavo-convex reflector 56 is 55 adjustably mounted at one side of the lamp 18 and a set of three cooperating plano-convex lenses 57, 58, and 59 are shown adjustably mounted at the other side of the lamp, all for the purpose of directing the proper light rays thru whichever of the image-bearing slides is, at any given time, interposed between the lamp and the lenses 60 65 within the lens holder 19.

The mirrors 20 and 21 will be mounted at the proper inclinations to convey the image from each picture slide to the proper position on the image receiving plate 12. It is by the use of these 70 mirrors that the apparatus is adapted to produce a large picture without requiring so great an amount of space to do so as has hitherto been deemed necessary.

75 It will be seen that the diverging rays of light issuing from the lens holder 19 are lengthened

out sufficiently to enlarge the image to the desired extent.

In the operation of the apparatus, owing to the fact that the adjacent teeth 35 of the driven gear have semi-circular notches between them 5 and these notches are intermittently engaged between eccentric pin 36 with which the driving gear is provided, said pin operates in a smooth and uniform manner upon the driven gear reducing strain and wear upon the apparatus. 10

I claim:

1. In a machine of the kind described, a casing, a source of light, reflecting means, a circular slide carrier comprising a disc, a plurality of polygonally arranged image slides mounted along the peripheral portion of said disc, a gear secured to the lower face of said disc, said gear having a hub portion projecting from the underside thereof and provided with an external circumferential groove, an upstanding tubular bearing member secured to 20 the floor of said casing, said bearing having an internal annular flange on which said hub portion is rotatably mounted, a tension spring mounted in a recess in the wall of said bearing member under pressure to bear upon a face of said groove, 25 said gear being the final gear of a train of gearing whereby said carrier is rotated, a driving gear having a driving element eccentrically fixed thereto in juxtaposition with said gear, means to mount and rotate said driving gear to cause said driving 30 element to engage with a tooth of said gear whereby to advance said carrier to pass said slides successively into display position between said light and said reflecting means, and an image receiver positioned to receive and display the 35 reflected image.

2. In a machine of the kind described, a casing, a source of light, reflecting means, a circular slide carrier comprising a disc, a plurality of polygonally arranged image slides mounted along the peripheral portion of said disc, a gear secured to the lower face of said disc, said gear having a hub portion projecting from the underside thereof and provided with an external circumferential groove, an upstanding tubular bearing member 40 secured to the floor of said casing, said bearing having an internal annular flange on which said hub portion is rotatably mounted, a tension spring mounted in a recess in the wall of said bearing member under pressure to bear upon a face of 45 said groove, said gear being the final gear of a train of gearing whereby said carrier is rotated, a driving gear having a driving element eccentrically fixed thereto in juxtaposition with said gear, means to mount and rotate said driving gear to cause said driving element to engage with a tooth of said gear whereby to advance said carrier to pass said slides successively into display position between said light and said reflecting means, braking means comprising a spring 50 operatively related to said gear to frictionally contact with the teeth thereof to prevent over-rotation of said carrier, and an image receiver positioned to receive and display the 55 reflected image.

3. In a machine of the class described, a circular slide carrier comprising a disc, a series of spaced slide holders upstandingly mounted along the peripheral portion of said disc, said holders comprising an angle iron post having a foot portion 70 whereby it is secured to said disc with the inner angle of the post directed towards the center of said disc, and an inner plate and an outer plate both of the same angularity as said post secured to the opposite sides of said post, 75

said outer plate having at each side of its lower end an inwardly directed flange to form a slide support for the adjacent ends of the picture slides when inserted between said plates.

5. 4. In a machine of the class described, a casing, a circular slide carrier comprising a disc, a series of spaced slide holders upstandingly mounted along the peripheral portion of said disc, said holders comprising an angle iron post having a foot portion whereby it is secured to said disc with the inner angle of the post directed towards the center of said disc, an inner plate and an outer plate both of the same angularity as said post secured to the opposite sides of said 10 post, said outer plate having at each side of its lower end an inwardly directed flange to form a slide support for the adjacent ends of the picture slides when inserted between said plates, a horizontally disposed gear secured to the lower 15 face of said disc, said gear having a hub portion projecting from its lower side, a tubular bearing member, having an internal annular flange upstandingly mounted on the floor of said casing, said hub portion being rotatably mounted within 20 said tubular bearing with the weight of said gear sustained by the internal flange of said bearing member, there being an external groove surrounding said hub portion, a tension spring cooperating with said groove, and a screw tapped thru 25 said bearing member exerting a pressure on said spring.

5. In a machine of the class described, a casing, a circular slide carrier comprising a disc, a series of spaced slide holders upstandingly 35 mounted along the peripheral portion of said disc, said holders comprising an angle iron post having a foot portion whereby it is secured to said disc with the inner angle of the post directed towards the center of said disc, an inner plate and an outer plate both of the same angularity 40 as said post secured to the opposite sides of said post, said outer plate having at each side of its lower end an inwardly directed flange to form a slide support for the adjacent ends of the picture 45 slides when inserted between said plates, a horizontally disposed gear secured to the lower face of said disc, said gear having a hub portion projecting from its lower side, a tubular bearing member, having an internal annular flange upstandingly mounted on the floor of said casing, said hub portion being rotatably mounted within 50 said tubular bearing with the weight of said gear sustained by the internal flange of said bearing member, there being an external groove surrounding said hub portion, a tension spring 55 cooperating with said groove, a screw tapped thru said bearing member exerting a pressure on said spring, a leaf spring having a seat bent thereinto at a point intermediate its end portions to 60 operate with the points of the teeth of said gear and said spring being provided with a braking surface near its free end to frictionally engage said teeth, and means to mount said spring in said casing in an operative relation to said gear.

65. 6. In a machine of the class described, a casing, a source of light, reflecting means, a circular slide carrier comprising a disc, a series of spaced slide holders upstandingly mounted along the peripheral portion of said disc and comprising 70 an angle iron post having a foot portion whereby it is secured to said disc with its inner angle directed towards the center of said disc, an inner plate and an outer plate both of the same angularity as said post, means to secure said angle plates with the opposite sides of said post, said

outer angle plate having at each side of its lower end an inwardly directed flange to form a slide support for the adjacent ends of the picture slides, a plurality of image slides detachably mounted in said holders, a horizontally disposed 5 gear wheel secured to the lower face of said disc, a wheel, an upstanding pin eccentrically mounted on said wheel, means to mount and rotate said wheel to cause said pin to successively contact with the teeth of said gear to intermittently pass 10 said slides successively into display position between said light and said reflecting means, an image receiver positioned to receive and display the reflected image, a leaf spring having a seat bent thereinto at a point intermediate its end 15 portions to cooperate with the points of said gear teeth and said spring being provided with a braking surface near its free end to frictionally engage said teeth to prevent over-rotation of said carrier, means to mount said spring in an operative 20 relation to said gear, said gear wheel having a hub portion projecting from its lower side, a tubular bearing member having an internal annular flange upstandingly mounted on the floor 25 of said casing, said hub portion being rotatably mounted within said tubular bearing with the weight of said gear sustained by the internal flange of said bearing member, there being an external groove surrounding said hub portion, a tension spring 30 cooperating with said groove, and a screw tapped thru said bearing member and exerting a pressure on said spring.

7. In a machine of the kind described, a source of light, reflecting means, a slide carrier comprising a disc having a series of polygonally spaced 35 slide holders upstandingly mounted along the peripheral portion thereof for detachably securing a plurality of image slides thereto, a gear secured to the under side of said disc, the roots of the teeth of said gear being struck with radii 40 whose centers are located in the same orbit as the path in which said gear rotates whereby the surfaces of said roots are uniformly curved, a driving gear having an eccentric upstanding driving element, means to mount and rotate said 45 driving gear to cause said element in its planetary movement to engage and move across the aforesaid curved surfaces of the roots of said teeth one at a time to intermittently drive and thereby rotate said carrier to pass said slides successively into display position between said light 50 source and said reflecting means in whichever direction said carrier may be rotated, means comprising a leaf spring having a seat bent thereinto at a point intermediate its end portions to 55 operate with the points of said gear teeth to prevent overrotation, and said spring being provided with a braking surface near its free end to frictionally engage one of said teeth incident to the seating of another tooth in said seat, and 60 an image-receiver positioned to receive and display the reflected image while the tooth of said gear is so seated.

8. The combination with an intermittently rotated slide carrier including a gear whereby it 65 is driven; of a leaf spring operatively related to the tips of the teeth of said gear, said spring having a seat wherein a tooth of said gear seats during rest periods of said carrier, said spring having its free end portion adapted to graze and 70 effect a braking action on an adjacent tooth.

9. The subject matter of claim 8 and, said braking action occurring principally when the first said tooth approaches and leaves said seat.
